UNITED STATES PATENT OFFICE

2,545,376

ELECTROLYTIC CELL WITH MERCURY
CATHODE

Runar Mauritz Rafaelsson Örnblom, Kuusankoski, Finland, assignor to Kymen Osakeyhtiö-Kymmene Aktiebolag, Kuusankoski, Finland

Application October 6, 1947, Serial No. 778,136
In Finland October 22, 1945Section 1, Public Law 690, August 8, 1946
Patent expires October 22, 1965

3 Claims. (Cl. 204—250)

1

The method of constructing electrolytic cells with mercury cathodes from rolled section iron is previously known. As the cell is generally trough shaped, U or I-shaped balks are mostly used. In the event that very large cells are constructed they may comprise a separate bottom part with upright walls attached in a convenient manner to the edges of the said bottom.

It is likewise previously known that the walls of such cells are lined with a chlorine gas resistant material such as rubber, artificial resin or plastics, acid proof enamel, or some other substance convenient for that purpose, and that the bottom of the cells is unlined because it is covered with a mercury film.

It is essential that this film of mercury, although covering the unlined bottom of the cell completely, be as thin as possible thus saving considerable quantities of mercury.

The main defects of the present cells constructed of rolled section iron are, firstly that during usage, when there is a certain consumption of mercury, bare regions appear on the bottom of the cell. In order that the formation of such bare regions be prevented the mercury film that is used as a cathode must be kept unnecessarily thick which, again, is uneconomic. This, however, is inevitable because otherwise hydrogen gas will develop on the bare regions resulting in a possible explosion. Furthermore, the bottom of the cell will corrode in the said bare places. The second notable defect is that the flowing speed of mercury in the present cells decreases at the edge between the bottom and the upright walls which decrease causes solid sodium amalgam to form at the edges of the mercury film during the electrolytic action. The said amalgam then begins to decompose and forms hydrogen gas. This amalgam coating also causes an accumulation of carbon particles and other impurities which render the circulation of mercury more difficult. All these disturbances in the usage of the cell make it necessary to take the cell apart for cleaning. The aforementioned defects can be regarded as very great especially when large cells of for example 10 to 12 meters in length are used, the strength of the current being 10,000 to 20,000 amperes, because the said disturbances may cause serious accidents and injuries. To prevent this the bottoms of the described cells are completely covered with a rubber coating through which the necessary electrodes are passed. This bottom coating is not very lasting, however, and thus a cell of the said type has proved to be uneconomic.

2

The object of this invention is to eliminate the said defects even when the largest type of barebottomed cells are used. The invention is based on the observation that the reason for the aforementioned disturbances lies therein that the bottom of a cell manufactured from rolled section iron is never completely level but always just enough curved or bent to necessitate the use of too much mercury because a theoretically sufficient thin film does not cover the bottom of the cell due to the great cohesive hold of the liquid, which fact has not previously been taken into consideration when constructing cells. It has also been observed that the decrease in the flowing speed of mercury is due to the fact that the edge between cell bottom and walls that are manufactured by the rolling process is rounded. Furthermore similar disturbances have been observed even in the smallest angles and uneven surfaces resulting from the rolling process. Contrary to previous beliefs the originators of the disturbances that have occurred when cells manufactured by the rolling process have been replanned are continually the faults in the form of the cell.

In conformity with the invention the described disadvantage is eliminated by accurate machining of the shaped plate, from which the respective cell bottom is made, so that the upper surface is planed to an absolute level. Likewise the edge between bottom and walls is machined to right angles with a fully developed edge, i. e., the rounded edge is eliminated.

An accurately machined bottom surface effects a considerable saving of mercury because the thickness of the mercury film in the invented cell under reference can be kept even and so thin that the bottom of the cell is just merely covered sufficiently. The 90 degree angle between the walls and the bottom guarantees that no disturbing amalgams can formulate at that region and also that the said region does not become uncovered.

In conformity with an especially favorable modification of the said invention the edges of the bottom that touch the side walls may be equipped with an encircling channel or trough which can be made by conveniently machining the respective edges of the shaped bottom plate. By this measure an even more effective means of preventing the edge surface of the mercury film from developing harmful phenomena is gained because the mercury flows with greater speed at the edges than on other regions of the bottom surface.

As has previously been mentioned similar cells have been lined completely with an insulating layer of, for example, rubber. The cell described in the invention has an insulating lining on the side walls only and in conformity with the invention the said lining is applied in a manner that leaves the lower end of the said lining below the mercury film in the channel encircling the bottom. This prevents the formation of uncovered regions on the iron surface of the cell bottom and consequently the formation of solid amalgam is also prevented.

In conformity with this favorable form of operation of the invention the length of the protective wall lining is increased at the end portion to reach a little over the bottom of the cell, and a strip made of steel, iron or some other metal or suitable substance of a convenient cut, is adjusted to press the said lining against the bottom of the groove made for this purpose, however, without letting the upper surface of the strip to extend above the surface of the cathode bottom.

The accompanying drawings describe preferred forms of the invention in operation: Fig. 1 features the corner angle portion of the invented cell constructed from an I-shaped balk. Fig. 2 features a form composed of separate bottom and walls. Figs. 3 to 6 feature cell portions the insulating wall lining of which are attached down with special strips. The drawings are all transverse sectional views.

Fig. 1 features the body of the balk acting as the bottom of the cell 1 and the upright ledge sections as the side walls 2. The surface of cell bottom 1 is accurately machined and absolutely level. The angle between the body and the ledge which the rolling process leaves rounded as shown in 3, is machined to a 90 degree angle 4 with fully developed ledge. The protective lining 5 on wall 2 reaches down below the mercury film. For this reason a trough 6 has been cut along the edge. Fig. 1 illustrates another groove or trough 7 along the side walls 5, 2 lower than the surface of the bottom of the cell.

Fig. 2 illustrates a cell the bottom of which has been made of a separate rolled, planed and machined bottom plate 8. In conformity with the invention this plate is equipped with troughs 9. The side walls are constructed of section iron, preferably U or L-shaped iron. Fig. 2 illustrates the side wall 10 made of a U-shaped, and the wall 11 supporting the cell at the bottom made of an L-shaped iron. Between the ledges of the reference section irons the bottom plate, or web 8, with its channelled edge is attached in a convenient manner. The bottom should be additionally supported from below with, for instance, a cross beam 12 to prevent the said bottom from bending.

Figs. 3 to 6 feature the following sections:

The wall 13 of the cell, the cathode bottom, or web 14, the groove or trough 15 encircling the cathode bottom 14 (the said groove may be of any convenient shape as shown in the reference illustrations), the protective chlorine gas proof lining 16 of the wall (this lining can be of ebonite, rubber, artificial resin or some other convenient chlorine resistant material), the lengthened lower section 16a of the reference protective lining inserted into a groove 15 cut for that purpose and covering the bottom of the said groove. The lengthened lower section is pressed against the bottom of the groove with the aid of an iron or steel band or strip 18

which is secured with a sufficient number of screws. The said strip 18 is screwed on so tightly that the possible shrinkage of the rubber lining cannot form an empty space between the wall of the cell and its lining. Figs. 3 and 4 feature a bracket 17 cut into the groove 15 alongside the inner edge of the lining. Strip 18 when secured into position will support itself against bracket 17. The reference bracket 17 prevents the pressure of strip 18 against lining 16a from being too severe. The width and height of bracket 17 may vary as shown in Figs. 3 and 4. In addition a cutting 19 may be machined into the lower section of the wall of the cell opposite groove 15, as shown in Fig. 4. This cutting 19 is equipped with extra insulation 20. In each case strip 18 must be screwed into position (with screw 21) so tightly that its upper surface does not extend above the surface of the bottom of the cell. Figs. 3 and 4 feature the cross section of strip 18 as rectangular in shape. However, to further safeguard a continuous resilient pressure against the protective lining in the groove, the cross section of the strip may be given an angle or curve shape as shown in Figs. 5 and 6. The advantage of such a shape lies therein that the bottom angle 22 of groove 15 being smaller than the corresponding angle of the strip before the said strip is secured into position, the sides of strip 18 will continue to keep up a resilient pressure against the base. The circumstance is similar when the strip is curve shaped (Fig. 6). The radius of a curve shaped strip's cross section is somewhat larger than the corresponding radius of the cross section of groove 15 before it has been screwed into position, and the strip is screwed on so tightly that it shapes itself in conformity with the groove. In the two latter instances it is necessary in order to acquire a resilient pressure that the cross section of the strip corresponds approximately with the shape of the groove. However, if the cross section of the strip is made into the shape of a triangle or segment, i. e. the upper surface of the strip is level when secured into position, the strip loses its resilience and is no longer appropriate.

Depending on the depth of groove 15 the said groove aiding the flow of mercury and located 50 along the edge of the cell bottom, can be acquired automatically and without the previously accurate machining which has been extremely difficult to perform.

It is preferable to adjust the heads of the securing screws into the strip as shown in Figs. 3 and 4 because the outer edges of the screw heads as shown in Figs. 5 and 6 naturally tend to form a slight obstacle for the flow of mercury which fact, however, has no significance in the two latter cases featured in Figs. 5 and 6 where the mercury film is thicker in the groove.

What I claim is:

1. An electrolytic cell with a mercury cathode comprising an integral iron structure in the form of an I beam in cross-section with the center web of said beam extending horizontally, a trough formed by the said center web and the said side walls provided by the upwardly extending arms of said I, the bottom of said trough being accurately machined throughout to provide a smooth flat horizontal surface, said side walls extending at right angles with respect to said surface; the bottom of said trough being formed with a groove between said machined surface and each of said side walls, a protective lining for said side walls

formed of material impervious to the decomposition products of electrolyte, said lining being secured to and covering said side walls and including a lower edge portion turned into and terminating within said edge groove, a securing strip overlying said turned portion of said lining, said securing strip being received within said edge groove and having its upper surface lying below said machined surface.

2. An electrolytic cell with a mercury cathode comprising, a trough formed of iron, said trough being generally U-shaped in cross section with the base of the U forming the bottom of the trough being accurately machined throughout to form an even flat upper surface, said upper surface and the side walls of said trough extending at exact right angles with respect to each other and said upper surface meeting the side walls of said trough at a definite edge, said machined upper surface being grooved along its edges adjacent said side walls, said side walls being provided on their interior surfaces with a protective lining impervious to the decomposition products of electrolyte, the lower end section of said lining extending down below said machined bottom surface of said cell and being turned to terminate in said edge groove with the upper surface of the turned portion of said protective lining lying below said machined upper surface of said bottom, and a securing strip seated in said groove to overlie said turned portion of said protective lining, said strip wholly covering said turned portion and securing said turned portion in place in said groove with the upper surface of said securing strip extending no higher than said machined surface.

3. An electrolytic cell with a mercury cathode comprising an iron structure formed with a horizontally extending center web and with side walls extending upwardly with respect to said center

10 products of electrolyte, said lining being secured to and covering said side walls, said lining including a lower edge turned into and terminating within said edge groove, a strip overlying the turned edge of said lining and received within said groove to hold said turned edge tightly in place in said groove, and means to secure said strip in place with no part of the top thereof extending above the main portion of said machined surface.
